UNITED STATES PATENT OFFICE.

ARTHUR P. BROWN, OF BRADLEY, MAINE.

TACKLE-BLOCK.

No. 823,989.

Specification of Letters Patent.

Patented June 19, 1906.

Application filed February 28, 1906. Serial No. 303,510.

To all whom it may concern:

Be it known that I, ARTHUR P. BROWN, a citizen of the United States, residing at Bradley, in the county of Penobscot and State of

5 Maine, have invented new and useful Improvements in Tackle-Blocks, of which the following is a specification.

This invention relates to blocks of the type employed in connection with hoisting-tackle, 10 being especially directed to the block-suspending hook, and has for its objects to provide a simple and efficient means for permitting convenient handling of the hook in the operation of suspending the block, one where- 15 by danger of the operator's hand becoming injured is obviated, and one whereby a rope or other element may be conveniently engaged with the hook to permit hoisting of the block to position for suspension.

20 With these and other objects in view the invention comprises the novel features of construction and combination of parts more fully hereinafter described.

In the accompanying drawings there is 25 shown a front elevation of a tackle-block equipped with a suspending-hook embodying the invention.

Referring to the drawings, 1 designates a 30 toggle-block provided with reeve openings or guides in which are journaled grooved pulleys 3, there being pivoted to the normally upper end of the block by means of a pivoting member or strap 4 a suspending member or hook 5, these parts, except as hereinafter explained, being all of the usual or any appropriate construction and material and adapted to perform their ordinary functions.

In accordance with my invention the suspending member or hook 5 is provided with a 35 rearwardly-projecting engaging portion or member 6, preferably in the form of an auxiliary downturned hook formed integral with

the body portion of the hook 5, adapted to be engaged in the operation of engaging the hook 5 with an overhead support from which 45 the block may be suspended.

It is customary in the operation of suspending tackle-blocks from an overhead support for the operator to grasp the shank of the hook 5, while engaging the latter with an eye 50 or the like upon the support, it being well known that under these conditions injury to the operator's hand frequently results. Furthermore, it has been the practice heretofore to hoist the block to a position for suspension 55 from the overhead support by means of a rope engaged with the hook 5, this method being objectionable to the extent that after the hook has been engaged with the supporting-eye considerable difficulty is experienced in 60 freeing the hoisting-rope from the hook. Under my improved construction the hoisting-rope may be engaged with the auxiliary hook 6 for hoisting the tackle-block to position for suspension, and the auxiliary hook may 65 be utilized as a handpiece to be grasped by the operator while manipulating the hook 5 for engaging the same with the supporting-eye.

Having thus described my invention, what 70 I claim is—

1. A tackle-block having a suspending member provided with a projecting engaging hook.

2. A tackle-block having a suspending- 75 hook provided with a rearwardly-projecting auxiliary engaging hook.

In testimony whereof I affix my signature in presence of two witnesses.

ARTHUR P. BROWN.
